(57) **CLAIM**

The ornamental design for a hand scrubbing pad, as shown and described.

DESCRIPTION

FIG. 1 is a front elevation view of a hand scrubbing pad according to the present invention;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front view of a second embodiment of a hand scrubbing pad;

FIG. 8 is a rear view thereof;

FIG. 9 is a left side view thereof;

FIG. 10 is a right side view thereof;

FIG. 11 is a top plan view thereof; and,

FIG. 12 is a bottom plan view thereof.

The broken line showing of a suction cup in FIGS. 1-9 is included for the purpose of illustrating and forms no part of the claimed design.
